UNITED STATES PATENT OFFICE.

JOHN C. ZACHOS, OF NEW YORK, N. Y.

SYSTEM OR METHOD OF REPORTING SPEECH.

SPECIFICATION forming part of Letters Patent No. 290,830, dated December 25, 1883.

Application filed January 26, 1883. (No model.)

To all whom it may concern:

Be it known that I, JOHN C. ZACHOS, of the city, county, and State of New York, have invented a new and useful System or Method of Reporting Speech, of which the following is a specification.

My invention consists of a special scheme of selected types or letters, which can be used to record signs of such sounds as are uttered in speech.

My invention further consists in the selection of one letter with its special phonic significance, standing invariably for one or more different sounds, as indicated by diacritic marks, and in the selection of one letter for two or more sounds that are similar or cognate.

In the drawings, Figure 1 represents the signs of sound constituting my phonic alphabet. Fig. 2 shows my phonic text in connection with the ordinary text, and Fig. 3 illustrates the proposed arrangement of my phonic text upon the key-board of a type-writing machine.

The following table of letters or phonotypes, with their phonic significance given in the accompanying words, may be printed or written in capitals or in small letters, and may be marked differently, according to the usage of pronouncing-dictionaries or spelling-books:

30 Vowel-Signs—twelve.

	Short sounds.	Long sounds.
35	À, as in Àt.	À, as in Àle.
	È, " " Èll.	È, " " Ève.
	Ì, " " Ìt.	Ì, " " Ìce.
	Ò, " " Òdd.	Ò, " " Òde.
40	Ù, " " Ùp.	Ù, " " Ùrm.
		Ö, " " Öil.
		Ö, " " Öut.

Cognate vowel-sounds not used but represented by the signs above given, and by the W.

45	À, as in Care, cognate to À, as in Àt.	
	À, " " All, " " Ö, " " Ödd.	
	Ù, " " Urn, " " Ù, " " Ùp.	
50	Ù, " " Müle, " " W, " " Woo,	
		(a semi-vowel.)
	Ü, " " Rüle, " " W, as in Woo,	
		(a semi-vowel.)
	Ü, " " Bill, " " W, as in Woo,	
		(a semi-vowel.)

Thus the eighteen vowel-sounds of English 55 speech are represented by thirteen signs in this phonic alphabet, with the help of diacritic marks over or under the same letter, or by the application of the principle that similar or cognate sounds may have the same sign. 60

The consonant-signs or phonotypes of the phonic text—fifteen.—Phonotypes, (used:) P, T, J, K, F, T, S, S, M, N, L, R, W, Y, H. Cognate sounds and signs in the alphabet, (not used:) B, D, Ch, G, V, Th, Z, Sh. To these 65 signs is added &, the sign for "and." These consonant-signs of sounds need no illustration, as they have the same as their most common significance in the English alphabet, with the exception of T and S, used to represent sounds 70 commonly written as "th" and "sh." Thus the forty-one "elementary sounds" of English speech are represented in the phonic text by twenty-seven phonotypes, and constitute a text in which all the elementary sounds are represented by the fewest different signs, either directly or indirectly through their cognates, 75 and yet made legible by its approximation to the common text of English. By this selection and device, brevity, economy, and legibility 80 are secured for a phonic text designed to report speech. Furthermore, this phonic text in its construction is put under the following rule, which distinguishes the phonic from the common text:

Rule for printing or writing the phonic text.—Print or write every word with the phonotype alphabet according to its elementary sounds, discarding all silent letters and all unaccented vowels of the common text of English, and using but one selected letter for its cognates in sound, where there are two or more cognate sounds in the language. This peculiar construction of a phonic text by the rule above gives it its distinction and originality, and secures uniformity with the greatest degree of brevity, economy, and legibility consistent with the exigencies of reporting speech by means of a text as near as possible to the present text of English. Under this rule of construction the following advantages are obtained for this phonic text: First, by the use of the phonic alphabet of signs or the phonotypes, every elementary sound in the language finds a representative, either directly or by an 95 approximate cognate sound, to which the sign is also attached; secondly, by the omission of silent letters and unaccented vowels, nearly 100 105

one-fourth of the letters used in the common text of English are omitted without impairing the legibility of words when read by sounds and signs corresponding; thirdly, by omitting 5 the unaccented vowels in speech, the most familiar and oft-recurring words in the language are reduced to a single letter, which gives great facility and speed in printing or writing this text without destroying the legibility of 10 the words when read by sound and sign corresponding. These most familiar and oft-recurring words are the following, and thus represented in the phonic text:

A=a or an.	H=he.
I=I.	T=the.
S=is or as.	L=will or all.
T=to, it, or at.	W=we.
N=in or on.	S=she.
F=of or if.	Y=you or ye.
M=am, my, or me.	&=and.

Here are fourteen letters, representing in all twenty-four words the most frequent in their recurrence, and forming with their combinations in such phrases as "of the"=FT, 25 "to the"=T^F, "in the"=NT^F, "are you"=YR, "I am"=IM, "he will"=HL, &c., from thirty to forty per cent. of the common text of English. A little practice soon familiarizes the reader with this and all its peculiarities, so that he can print, write, and read the phonic text with ease.

The following is given as a specimen of the phonic text and its strict adherence to the signs, the rule, and the method of representing the very common words, as heretofore described:

In the beginning God created the Heavens
N T PKINN KÖT KRÄTT T HÉFNS
40 and the earth; and the earth was without
& T RT & T RT WS TÖT
form and void, and darkness was upon
45 FÖRM & FÖT, & TÄRKNS WS PÜN
the face of the deep.
T FAS F T TEP.

The result of this determinate constitution 50 of the phonic text is, that whereas the common text of English requires on the average from five to six letters to the word, and consequently from five to six touches (including the space between words) on a key-board designed to print the common text, the phonic text requires on the average three touches for the word (including the space) on a key-board designed to print this text; hence the words can be printed phonically nearly twice as fast as 55 in the common orthography, with the same number of touches employed on the ordinary type-writer; and if this system of notation is used without any mechanical means for recording the text the writer will be able to discard a corresponding number of characters.

65 When it is desired to use my system of phonotype notation in connection with a me-

chanical means for recording the several characters, I propose to arrange the characters which I have described in columns by classes, 70 as is shown in the drawings. The letters or signs of sound are purposely so arranged as to help the memory in a quick demand for their location, and a useful application of their significance as signs of sound or of words in 75 printing by a type-writer instrument; hence all letters of the same denomination, with the exception of a few, are placed on the same horizontal line. The perpendicular rows are also arranged in duplicate or triplicate rows, 80 except where there were no duplicates of the letters or figures required. The first three columns of letters on the right, as shown in the drawings, are devoted to certain oft-recurring words in speech, which, having no 85 accented vowel and only one consonant-sound, can be represented in the phonic text by a single consonant letter, according to the rule of construction. These words and corresponding letters are the following:

Col. 1.	Col. 2.	Col. 3.
&=and.	M=am.	A=a or an.
I=I.	H=he.	L=will.
T=The.	S=is or as.	S=is or as.
T=to, at, or it.	T=to, at, or it.	W=we.
N=in or on.	T=the.	S=she.
F=of or if.	R=are.	Y=you.

Here are fourteen different letters, representing in all twenty-four words the most commonly recurring in any English text, and forming with their combinations in such phrases as "of the," "to the," "in the," "are you," "I am," &c., from thirty to forty per cent. of the common text of English. Their location, as introductory words and phrases in speech, put uniformly before other words with which they are connected in sense, will almost always distinguish them from the other words and letters of the text.

100 Examples.
In the house, to the man, for we trust, &c.
N T HÖS, T T MÄN, FR W TRÜST.

105 The next two columns are devoted to such consonant-sounds as precede the vowel-sounds in the formation of words in this phonic text. Here all combinations of consonant-sounds are provided for by placing S at the beginning and L and R at the end in the order of such combinations of consonants, as shown in the drawings.

110 Examples.
Split, Scroll, Spring =words.
34578, 34568, 34578 =columns.
SPLIT, SKRÖL, SPRIN =phonic.

115 In the above the figures indicate the order of the letters in the columns according to the number of the column. The columns marked 120 6 and 7 provide signs for all the vowel-sounds of the language; with W when used as a vowel-sound, in column 8. This selection is made in accordance with the phonic alphabet

heretofore described, and furnishes all the vowel elements desired in the printing of the phonic text. In the columns marked 8 to 12, inclusive, are all the signs of sounds that the 5 aforesaid phonic alphabet furnishes for the presentation of the elementary sounds of the phonic text, in all combinations which can occur after the accented vowel of words. Six letters in one column—M, L, S, T, N, R—are 10 triplicated in three columns, (except the W in column 8,) and six letters—T, J, F, K, S, P—are duplicated in two columns. This arrangement, with the help of T and S in column 13, gives the command of all consonant-sounds after the accented vowel of words printed in this 15 phonic text. By the arrangement illustrated words can be set by one span of the hand on a key-board. Column 13 contains the hyphen (-) and period (.), which are duplicated in column 15. It contains also the dollar-mark (\$), and, besides the T and S before mentioned, it 20 has the y, used as the sign of the last sound in pity, duly, many, &c., very often recurring in English. The columns 14 and 15 are devoted to 25 the ten digits for recording numbers, and a du-

plication of the hyphen and period. This completes the arrangement of letters, signs, and figures for use on a key-board, designed, with the help of suitable mechanism, to set upon a line and print words, parts of words, and short 30 phrases and numbers in the phonic text heretofore described.

Having thus fully described my invention, what I claim, and desire to secure by Letters Patent, is—

1. In a system of phonotype notation, the herein-described arrangement of selected letters and signs, with their respective diacritical marks arranged and combined for the formation of a text, substantially as described. 35

2. The herein-described text for reporting speech, which consists of a phonic alphabet composed of selected letters with their respective diacritical marks, substantially as described. 40
